UNITED STATES PATENT OFFICE.

PAUL GEHRMANN, OF DRESDEN, GERMANY.

CARBURETER.

1,086,287.

Specification of Letters Patent.

Patented Feb. 3, 1914.

Application filed February 17, 1913. Serial No. 748,886.

To all whom it may concern:

Be it known that I, PAUL GEHRMANN, a subject of the King of Saxony, residing at Dresden, Kingdom of Saxony, German Empire, have invented certain new and useful improvements in Carbureters, of which the following is a specification.

This invention relates to a carbureter for motor-cars which is constructed in such a manner that the engine works without vibrations even when the vehicle runs at a low speed. This is obtained by the favorable formation of the gaseous mixture resulting from the simultaneous use of two perforated rings the openings of which are closed by balls and which serve for the supply of main air and of supplementary air.

In the accompanying drawings the invention is shown by way of example.

20 Figure 1 is a vertical section of the carbureter. Fig. 2 is a part horizontal section on the line A—B of the Fig. 1.

The conduit *a* for the main air is surrounded in the well known manner by the fuel reservoir *b* mounted upon a circular flange *c* of the carbureter casing. The fuel reservoir *b* is closed at the top by a lid *d* upon which a flat ring *e* is arranged which has a great number of air holes *f*. These air holes communicate with recesses *g* in which ball valves *h* are located. In the ring *e* a tubular socket *i* is mounted which has a throttle valve *k* of known construction. The tube *i* is screwed into the upper end of conduit *a* and it has a shoulder resting on the top of the cover *l* so that it holds this cover and the ring *e* in place. The recesses *g* communicate with the tube *i* by means of air ports *n*. The ring *e* has vertical extensions *x*, one for each air port *n*, which bear against the outer surface of the tube *i*. These extensions are of the same width as the spaces between the ports *n* and serve the purpose of valves when ring *e* and cover *l* are rotated to partially or wholly close ports *n*.

In the vertical upper end of the air conduit *a* a cylindrical piece *o* is screwed which has an inner boring of double conical cross section. The spraying nozzle *p* is situated in said cylindrical piece *o*. The nozzle is regulated by means of a pointed needle valve *q*. The cylindrical piece *o* has a lateral flange *r* which is perforated by holes *s* the upper ends of which are closed by ball

valves *u*. Above the flange *r* an annular chamber *t* is formed. A cover *v* projecting over the upper end of said annular chamber *t* serves for maintaining the balls in said chamber.

The main air flows into the carbureter 60 through the conduit *a* in the direction of the arrow; it is throttled in the narrow part *w* of the boring of the cylindrical piece *o* before it gets into the tubular socket *i* which serves as mixing chamber. Part of the main 65 air passes through the holes *s* of the flange *r* and lifting the ball valves *n* flows through the annular chamber *t* along the inner edge of the cover ring *v* into the mixing chamber *i*. The supplementary air is admitted into 70 the mixing chamber *i* through the holes *f* of the ring *e*, said air lifting the ball valves *h* off their seats. The perforated ring *e* and the ring shaped cover *l* being rigidly connected the one with the other, they can be 75 turned around the mixing chamber *i* whereby the air inlets *n* are more or less covered by the extensions *x* of said ring *e*.

I claim:

Carbureter for motor cars comprising in 80 combination with the main air conduit, the spraying nozzle, and the mixing chamber having air inlets for the supplementary air, a horizontal ring having a certain number of perforations revolvably mounted upon 85 said mixing chamber under said air inlets, ball valves upon the upper ends of said perforations, vertical extensions of said ring one for each air inlet of the mixing chamber, a ring shaped cover screwed upon said 90 horizontal perforated ring and bearing with its inner end against the outer wall of said mixing chamber above said air inlets, a cylindrical piece in the conduit for the main air surrounding the upper end of said 95 spraying nozzle and screwed into said air conduit, a perforated horizontal flange of said cylindrical piece and ball valves upon the upper ends of said perforations, substantially as described and shown and for 100 the purpose set forth.

In witness whereof I have hereunto set my hand in the presence of two witnesses.

PAUL GEHRMANN.
